(57) **CLAIM**

The ornamental design for a sports goal, as shown and described.

DESCRIPTION

FIG. 1 is a front elevation view of the sports goal showing my new design;

FIG. 2 is a rear elevation view thereof;

FIG. 3 is a left side elevation view thereof;

FIG. 4 is a right side elevation view thereof;

FIG. 5 is a top view thereof;

FIG. 6 is a bottom view thereof;

FIG. 7 is a top, front and left perspective view thereof; and,

FIG. 8 is a bottom, front and left perspective view thereof.

The shading lines shown in the accompanying drawings represent three-dimensional surface contour only and do not depict any texture, color, shading or other characteristic.
